(57) **CLAIM**

I claim the ornamental design for a ring binder insertion carrier, as shown and described.

DESCRIPTION

FIG. 1 is a perspective view of the ring binder insertion carrier embodying the design;

FIG. 2 is a top plan view of the ring binder insertion carrier of FIG. 1;

FIG. 3 is a right side elevational view of the ring binder insertion carrier of FIG. 1;

FIG. 4 is a left side elevational view of the ring binder insertion carrier of FIG. 1;

FIG. 5 is a bottom plan view of the ring binder insertion carrier of FIG. 1;

FIG. 6 is a front elevational view of the ring binder insertion carrier of FIG. 1;

FIG. 7 is a rear elevational view of the ring binder insertion carrier of FIG. 1; and,

FIG. 8 is a perspective view of the ring binder insertion carrier of FIG. 1 shown in its environment mounted to the back portion of a geometry kit case.

The broken lines in FIG. 8 are for illustrative purposes only and form no part of the claimed design.
